UNITED STATES PATENT OFFICE.

EDWARD F. WESTON AND GRANT CARPENTER, OF NEWARK, NEW JERSEY, ASSIGNEES
TO WESTON ELECTRICAL INSTRUMENT CORPORATION, OF WAVERLY PARK, NEW-
ARK, NEW JERSEY, A CORPORATION OF NEW JERSEY.

ELECTRICAL MEASURING INSTRUMENT.

Application filed June 24, 1925. Serial No. 39,362.

This invention relates to an electrical measuring instrument of the well known movable coil type.

The main object of the invention is a simplification of the construction and arrangement of the parts of such an instrument whereby, without sacrificing sufficient accuracy, the cost of manufacture is materially cheapened.

10 One method by which this object may be attained is by making the base of rigid insulating material, preferably of molded material, such as "bakelite," which can be molded to exact dimensions, and so constructing 15 and arranging the parts that the base itself serves as the support or frame for holding the parts in proper allocation.

A feature of importance is the mounting 20 of the soft iron core, about which the moving coil swings, on an insulating support extending upwardly from the base plate and preferably formed as an integral part thereof.

The manner of securing the end of the 25 lower spring to the moving coils is also a new feature in that this end of the spring is directly connected to the base.

Still another feature of novelty is the 30 mounting of the moving system on pivots one of which is located in the base itself, while the other pivot is carried by a member connected to the base and preferably formed integrally therewith, this member being 35 preferably the insulating support which carries the core.

Still another feature of novelty is the construction and arrangement of the permanent 40 magnet, so that it can be readily removed without disturbing the moving system, which thus becomes readily accessible for inspection and repair.

Other features of novelty will appear from the following description.

Referring to the drawings:

45 Fig. 1 is a plan of the instrument, drawn to about twice the scale of the commercial device;

Fig. 2 is a similar plan with the case removed;

50 Fig. 3 is a section on plane 3—3 of Fig. 2;

Fig. 4 is a perspective view of the permanent magnet;

Fig. 5 is a perspective view of the base plate;

Fig. 6 is a detail showing the manner of 55 mounting the permanent magnet; and

Fig. 7 is a section showing the bridge pieces molded into the base.

The permanent magnet 1, as shown in Fig. 4, is preferably made up of stamped 60 steel plates, each of substantially annular form and having its ends so shaped as to form a cylindrical recess within which is mounted the moving system. The stamped out plates after hardening can be strongly 65 and permanently magnetized.

No separate pole pieces are used, the ends of the laminæ being so shaped, as shown, to surround the moving system. The laminæ are held in assembled relation by means of 70 fastening device 37 at the back and by nuts 35 and rings or nuts 40 on the bolts 13 and 14, the bolts passing through openings 11 and 12 in the base plate (see Fig. 6) in which they are held in place by nuts 41. By 75 removing the face plate and these nuts 41, the magnet as a whole may be removed bodily, thus leaving the moving system attached to the base but open for inspection and repair. This feature of construction we re- 80 gard as new.

While it is preferred to use a laminated magnet, it may be desirable, particularly in larger sizes of instruments, to use annular shaped bar magnets in which the pole pieces 85 are machined out of the magnets, or attached thereto in any convenient manner.

The novelty of our invention mainly resides in that the base plate of molded insulating material, such as "bakelite," is constructed and arranged to directly support most of the essential parts of the instrument. Necessity for separate electrical insulation of circuit connections is thereby avoided, and assemblage is greatly facilitated.

Thus, referring to Fig. 5, the base plate 2 has molded therein the screw threaded pin 3 for supporting the resistance coil 4, the bridge supports 5 and 6, the terminal pin 7, and the sleeve 8 in which the lower jewel 100 support is mounted. The base also has molded therein the necessary openings, such as 9 and 10, for the main terminals, and 11 and 12 for the bolts 13 and 14 supporting the permanent magnet. The base is rabbed to receive the cylindrical metal casing 105 which carries the glass cover.

The moving coil is provided at top and

bottom with pivot pins which bear on jewels carried by adjustable screw members, 17, 18, the latter being mounted in the sleeve 8 and the former in a bridge member 19, carried 5 by the pins 5 and 6. The sleeve 8 may be omitted and the jewel screw 18 threaded directly into a tapped hole in the base.

We believe it to be essentially new to mount the movable coil on pivots one of 10 which is carried by the base itself, and the other on a bridge element also directly attached to and carried by an integral part of the base.

A further important feature of novelty is 15 the mounting of the soft iron core 20 directly on an upstanding projection 21, formed in the molding as an integral part of the base. The core 20 is held in adjusted position by a screw pin 22.

20 The pointer 23 has the usual balancing arms 29 and is clamped to the movable coil by suitable nuts on the upper pivot pin.

The ends of the movable coils are electrically connected to ends of hair springs 24, 25 whose other ends are secured to abutments or arms 26, 31. The abutment 26 is secured to the spring washer 28, held against rotation by a tongue 42 (Fig. 1) extending into an opening in the bridge piece 19. The 30 abutment 31 is secured to the terminal pin 7, molded into the base, and this means of anchoring the spring directly to the base is also a new feature.

The spring washers 27, 28, hold the 35 jewel-bearings in proper adjustment, the spring washer 27 being held against rotation by a tongue extending into an opening in the base, as shown in Fig. 3.

The circuit connections are as follows:— 40 from the terminal 30 to resistance coil 4, pin 7, arm 31, lower hair spring 25, coil 16, upper hair spring 24, bridge piece 19, connector 32 and the second terminal 33.

It will be noted that throughout this 45 circuit, no insulation other than that afforded by the base itself is needed.

The base itself, constructed as described, constitutes the rigid frame on or in which are carried the pivotal supports for the 50 moving coil and the soft iron core, as well as the locating means for positioning the permanent magnet, thereby affording means for readily and exactly locating the essential parts of the instrument.

55 It is also an important feature of the invention that it makes possible the manufacture of small-sized high grade instruments (e. g. voltmeters) such as are now required in radio sets, at low cost.

60 We claim:

1. In an electrical measuring instrument, a base of insulating material, a permanent magnet having adjacent pole pieces, a movable coil pivoted between said pole pieces, 65 and a stationary core supported in position

within the coil by an upstanding portion of said base.

2. In an electrical measuring instrument, a base, a permanent magnet having adjacent pole pieces, a movable coil pivoted between 70 said pole pieces, and a stationary core supported in position within the coil by an upstanding portion of said base.

3. In an electrical measuring instrument 75 a base, a permanent magnet having adjacent pole pieces and supported directly on said base and freely detachable therefrom, a moving coil pivoted between said pole pieces, one of the pivot supports for said coil being located in the base and the other 80 pivot support carried on a bridge piece secured to an upstanding portion of said base.

4. An electrical measuring instrument as claimed in claim 3 having a stationary core supported in position within the coil by an 85 upstanding portion of said base.

5. In an electrical measuring instrument, a base of insulating material, a permanent magnet having adjacent pole pieces, a movable coil pivoted between said pole pieces, 90 one of the pivot supports for said coil being located in the insulating base and the other pivot support carried on a bridge piece secured to an upstanding portion of said insulating base. 95

6. An electrical measuring instrument as claimed in claim 5 having a stationary core supported in position within the coil by an upstanding portion of said base.

7. In an electrical measuring instrument, 100 a base of insulating material, a permanent magnet having adjacent pole pieces, a movable coil pivoted between said pole pieces, one of the pivot supports for said coil being located in the insulating base and the other pivot support carried on a bridge piece 105 secured to an upstanding portion of said insulating base, springs for controlling the movements of the coil, one of said springs being anchored to the base of the instrument. 110

8. In an electrical measuring instrument a base, a permanent horse-shoe magnet supported directly on said base and freely detachable therefrom and having spaced 115 curved pole pieces, a moving system carried on upper and lower supports independently of said magnet upon said base, a needle attached to said moving system, said needle and upper support being of less width than the gap between the pole pieces, said moving system being of less diameter than the curved space between the pole pieces, whereby the magnet and pole pieces may be removed without disturbing the moving system. 120

9. In an electrical measuring instrument a base of insulating material, a permanent horse-shoe magnet carried by said base and 125 having integrally formed curved pole pieces, 130

a movable coil pivoted between said pole pieces, a lower pivot support for said coil being located in the base, an upper pivot support carried on a bridge piece secured to an upstanding integral portion of said insulating base, and a stationary core supported in position within the coil by said upstanding portion.

10. In an electrical measuring instrument a base of insulating material, a permanent horse-shoe magnet carried by said base and having integrally formed curved pole pieces, a movable coil pivoted between said pole

pieces, a lower pivot support for said coil being located in the base, an upper pivot 15 support carried on a bridge piece secured to an upstanding integral portion of said insulating base, and a stationary core supported in position within the coil by said upstanding portion, the coil being provided 20 at its lower end with a control spring connected to the insulating base.

In testimony whereof, we affix our signatures.

EDWARD F. WESTON.
GRANT CARPENTER.
